(57) **CLAIM**

The ornamental design for a smart mirror with tablet, as shown and described.

DESCRIPTION

FIG. 1 is a top, front, right perspective view of a smart mirror with tablet, showing the new design;

FIG. 2 is a bottom, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The portions of the smart mirror and tablet depicted in broken dashed lines form no part of the claimed design. The claim is shown with a symbolic break in the length of the connection between the smart mirror and tablet. The appearance of any portion of the connection between the symbolic break forms no part of the claimed design.
